C. T. WESTLAKE & C. S. SHALLENBERGER.

DRAW BAR CARRY IRON.

APPLICATION FILED MAR. 23, 1914.

1,157,070.

Patented Oct. 19, 1915.

UNITED STATES PATENT OFFICE.

CHARLES T. WESTLAKE AND CHARLES S. SHALLENBERGER, OF ST. LOUIS, MISSOURI,
ASSIGNORS TO FLORY CARRY IRON COMPANY, OF ST. LOUIS, MISSOURI, A COR-
PORATION OF DELAWARE.

DRAW-BAR CARRY-IRON.

1,157,070.

Specification of Letters Patent. Patented Oct. 19, 1915.

Application filed March 23, 1914. Serial No. 826,563.

To all whom it may concern:

Be it known that we, CHARLES T. WESTLAKE and CHARLES S. SHALLENBERGER, citizens of the United States, residing at city 5 of St. Louis, State of Missouri, have invented a certain new and useful Improvement in Draw-Bar Carry-Irons, of which the following is a full, clear, and exact description, such as will enable others skilled 10 in the art to which it appertains to make and use the same, reference being had to the accompanying drawings, forming part of this specification, in which—

Figure 1 is a top plan view of a striking 15 plate with which a carry iron of our improved construction is combined. Fig. 2 is a front elevational view of the carry iron in position on the striking plate. Fig. 3 is a vertical section taken approximately on the 20 line 3—3 of Fig. 2. Fig. 4 is a top plan view of one end of the carry iron. Fig. 5 is a perspective view of one of the carry iron hangers.

Our invention relates to new and useful 25 improvements in supports or hangers for the draw bars of railway cars, the principal object of the invention being to provide a comparatively simple hanger which, under all conditions, will readily accommodate 30 itself to the backward and forward movement of the draw bar resulting from draft and buffing strains, and to the lateral swing or movement of said draw bar resulting from the passage of cars around curves in the 35 track.

In view of the fact that the length of movement of a supported draw bar is practically equal in both directions, that is, longitudinally and transversely, the carry iron 40 which supports said bar should be permitted to move freely in both directions and in order to prevent the draw bar from sliding upon the surface of the carry iron, the latter should be supported in such a manner as to 45 permit the draw bar to move longitudinally and transversely at the same time. To accomplish this result we propose to mount the carry iron upon hangers which are supported from a fixed part of the carry iron, 50 preferably the striking plate, by universal joints of the ball and socket type, which arrangement permits the carry iron to move

freely in all directions under the influence of the supported draw bar.

A further object of our invention is to 55 provide a draw bar hanger or support which can be readily assembled or taken apart, and which when in position for use, cannot become accidentally displaced by reason of undue vibration or jolting of the car draw 60 bar.

With the above and other objects in view, our invention consists in certain novel features of construction and arrangement of parts, hereinafter more fully described and 65 claimed.

Referring by numerals to the accompanying drawings, 10 designates the base of the striking plate which is applied to a car end sill or buffer beam in any suitable manner, 70 and formed integral with said base and projecting forwardly therefrom is a horizontally disposed plate 11, and formed integral with the front edge of this plate is a vertically disposed plate 12, which constitutes the 75 striking plate *per se*.

The plates 11 and 12 are reinforced and strengthened by suitably located integral ribs or flanges 13, and formed integral with the underside of the plate 11 and spaced 80 a suitable distance apart are depending lugs 14, which serve as stops to limit the transverse swinging movement of the supported draw bar. Formed in the end portions of the plate 11 are apertures 15 and 16, and 85 the edges of the plate around these apertures are counter-sunk or cut away so as to form concave seats or sockets 17 for the heads of the carry iron hangers hereinafter described.

A slot 18 is formed from the opening 16 to the corresponding end of the plate 11 to permit the corresponding hanger to be inserted in this opening when the device is 95 assembled, and to mount the device in its assembled position a pin or bolt 19 is seated in a pair of the ribs or flanges which occupy positions adjacent to and on opposite sides of said slot 18.

One of the hangers forming a part of our 100 invention is shown in Fig. 5, the same comprising a shank 20 with the upper end of which is formed integral a head 21, the underside of which is convex as designated

by 22 so as to fit snugly on the corresponding concave seat 17. The lower end of the shank 20 is provided with a pair of oppositely arranged horizontally disposed bearings or 5 trunnions 23.

The carry iron contemplated by our invention is formed in a single piece preferably by casting, and comprises a pair of heads 24, and an intermediate body portion 10 25 which is provided with a pair of oppositely disposed bearing faces 26, the same being preferably convex in cross section. One of these bearing faces is located nearer to the longitudinal axis of the carry iron than 15 the other, and thus by reversing the position of said carry iron or turning it upside down, the height at which the supported draw bar is carried can be varied.

Formed through the heads 24 are vertically disposed inwardly extending slots 27, and formed in the upper and lower faces of 20 said heads to the sides of these slots are seats or bearings 28 which are adapted to receive the journals or trunnions 23 on the lower 25 ends of the carry iron hangers.

In assembling our improved draw bar support, one of the hangers 20 is inserted through the opening 15 until the head of 30 said hanger rests upon the corresponding seat 17. One end of the carry iron 25 is now positioned on the lower end of this hanger with the trunnions 23 seated in the corresponding bars 28, after which the carry iron is swung upward into position beneath the 35 draw bar A. The lower end of the second hanger is now engaged in the corresponding end of the carry iron, after which the upper portion of this hanger is swung inward through the slot 18 so that the head of 40 this hanger occupies the seat around the edge of the opening 16. The pin or bolt 19 is now placed in position across the slot 18, thereby providing retaining means for preventing the accidental displacement of the 45 device when it is in use. As the supported draw bar, shown by dotted lines in Figs. 2 and 3 moves longitudinally of the car, under 50 buffing or pulling strains, the carry iron will swing backward or forward with said draw bar, and during this movement, the convex undersides of the heads 20 operate freely in the concave seats 17. During the transverse movement of the supported draw bar which takes place during the passage of the car 55 around a curve in the track, the carry iron on the lower ends of the hangers 20, swings transversely of the car, and during this

movement the heads 22 bear in their respective seats 17.

By our improved construction the hangers 60 for the carry iron are provided at their upper ends with substantially universal joints of the ball and socket type, and by virtue of this construction, the supported draw bar can move longitudinally and transversely at the same time, without appreciable wear or strain upon any of the parts of the support.

The entire carrier is comparatively simple, can be easily and cheaply manufactured, 70 and is capable of being readily assembled or taken apart.

We do not desire to be limited to the exact arrangement and details of construction herein shown and described, as it will be readily understood that the principles and characteristic features of the invention may be embodied in other devices differing specifically in detail more or less from those 75 herein shown and described.

We claim:

1. In a draw bar carrier, the combination with hangers provided at their lower ends with trunnions, of a carry iron provided with a pair of oppositely disposed draw bar 85 bearing faces, the same being located at different distances from the longitudinal axis of the carrier, the end portions of said carry iron being provided with slots, and oppositely disposed pairs of bearings formed in 90 the end portions of said carry iron to the sides of the slots therein which bearings are adapted to receive the trunnions on the hangers.

2. In a draw bar carrier, a support provided with openings, there being sockets formed around said openings and there being a slot formed in said support from one of the openings therein to the end of said support, hangers, heads on the upper ends 100 thereof, which heads are adapted to engage in the sockets around the openings, a carry iron pivotally connected to said hangers, and a removable member seated in the support and bridging the slot therein.

In testimony whereof we hereunto affix our signatures in the presence of two witnesses, this 6th day of March, 1914.

CHARLES T. WESTLAKE.
CHARLES S. SHALLENBERGER.
